UNITED STATES PATENT OFFICE.

CHARLES J. WAGNER, OF FORT LUPTON, COLORADO.

CLEANING COMPOUND.

No Drawing.

Application filed March 8, 1922. Serial No. 542,112.

To all whom it may concern:

Be it known that I, CHARLES J. WAGNER, a citizen of the United States, residing at Fort Lupton, in the county of Weld and 5 State of Colorado, have invented certain new and useful Improvements in Cleaning Compounds, of which the following is a specification.

This invention relates to cleaning compounds, and the general object of the invention is to provide a compound of this character which has been found in practice to be extremely effective and which will 10 cleanse clothes without the necessity of any scrubbing or agitation of the clothes.

A further object is to provide a compound of this character which will not only act as a detergent but will have more or less of an antiseptic effect upon the clothes, and further so form the compound that the clothes 20 are "blued" at the time they are washed.

Other objects will appear in the course of the following description.

My improved compound consists of the following ingredients in approximately the proportions stated, namely sal soda (carbonate of soda) three-fifths part, sulphur one-fifth part, bluing one-tenth part, and oil of turpentine one-tenth part. The compound of the above ingredients may be either 25 in liquid form, powder or flake form or in a tablet form.

The carbonate of soda acts to soften the water into which the clothes are placed, the bluing acts to whiten the clothes and to give them the slight blue tinge which is necessary, and the sulphur acts as a bleacher for the clothes and also tends to destroy parasites, either vegetable or animal. The turpentine not only acts as a solvent for the sulphur, which would otherwise be insoluble 35 in water, but acts to cut the grease in the clothes and to remove stains therefrom.

In the use of this compound, the water in which the washing is to be done must be 40 boiling. Then the compound is placed in the water, the amount of the compound to be used depending entirely upon the size of the wash. The boiling is continued for two 45 minutes after the compound has been placed

therein, and then the clothes are put into the boiling water. The clothes must be perfectly dry before being put in the water and should not be even damp. Enough soap should be used to make a suds in the boiling 55 water before putting in the clothes. After a suitable period the clothes are removed and thoroughly rinsed in lukewarm water and then rinsed in cold water and hung up to dry. The whole operation of washing under these circumstances for a large family 60 can be accomplished within less than an hour and the clothes, without any rubbing or scrubbing, will be found to be thoroughly 65 cleansed and white.

Actual test has shown that this compound will not injure the most delicate fabric and that it entirely does away with any necessity of rubbing the clothes and the consequent wear. The compound is very cheap, 70 and it will be obvious that no skilled manipulation of the compound or of the clothes is necessary.

While I have stated the proportions of the ingredients as being the proportions which 75 form a thoroughly effective compound, I do not wish to be limited to these proportions as these may be varied and, as I stated before, the compound may be put up in either liquid, powder, or tablet form.

Where the washing compound is to be put up in tablet form, I heat the dry soda and bluing to a lava-like condition, then add sulphur and the turpentine, the turpentine being added last. When cool it becomes 85 hard. It may be formed in any shape desired or be ground up so as to form a flake or powdered material. Where the compound is in the form of a liquid, the compound is mixed with water, the turpentine being 90 emulsified in the water.

I claim:—

A cleaning compound consisting of the following ingredients in substantially the following proportions:—carbonate of soda 95 three-fifths part, sulphur one-fifth part, turpentine one-tenth part, bluing one-tenth part.

In testimony whereof I hereunto affix my signature.

CHARLES J. WAGNER.
